UNITED STATES PATENT OFFICE

FRED PICKEL AND WILLIAM VON POELGEEST, OF NORTH BERGEN, NEW JERSEY

WINDOW SASH CONSTRUCTION

Application filed July 9, 1931. Serial No. 549,639.

This invention relates to glazed window sashes as used in dwellings, offices and like buildings and particularly to windows in which inner and outer sashes are slidably arranged, the same being an improvement over my co-pending application, filed February 18, 1931, Serial No. 516,551.

Such windows require cleaning at frequent intervals, an operation difficult and dangerous to perform, due to the inability of easy access to the outer surface of the sashes as ordinarily engaged between the side members of the window frame in which they slide.

It is therefore an object of the instant invention to provide a window having its slideable sashes provided with pivots arranged in a vertical plane whereby they may be swung inwardly, in the manner of a hinged door, when in a lowered position.

A further feature is in the provision of devices in the form of simple attachments whereby conventional slideable sashes may, upon being supplied with the attachments, be turned to present their inner surface in a convenient position for cleaning and like operations.

A further object is the provision of fittings by the use of which conventional vertical sliding double hung sashes may be converted into swinging sashes to make their outer surfaces accessible from the room.

These several objects are accomplished by the novel construction and arrangement of few, simple and inexpensive parts, and without material change in structure, as herein-after described and shown in the accompanying drawings, forming a material part of this disclosure, and in which:

Fig. 1 is a front elevational view of a conventional type of window showing the application of embodiments of the invention.

Fig. 2 is a fragmentary front view showing the lower left hand corner of a window frame and sash as fitted with the devices.

Fig. 3 is a vertical sectional view taken through the inner and outer sashes, and showing the attachments in operative position.

Fig. 4 is a transverse sectional view of the same, the sash showing in broken lines as being partially turned inwardly.

Fig. 5 is a partial front view, similar to Fig. 2, but showing a modified form of construction.

Fig. 6 is a vertical sectional view of the same.

Fig. 7 is a transverse sectional view thereof.

Fig. 8 is another partial front elevational view showing a further modification.

Fig. 9 is a vertical sectional view of the structure shown in Fig. 8.

Fig. 10 is a transverse sectional view of the same.

The window sash frames, seen in all of the several views, are all of the ordinary, well known type of construction, consisting mainly of a pair of upright stiles 10, connected at their tops by a cross piece 11 and having at their bottoms a sill 12, which may carry a cleat 13.

The sashes 14 and 15, respectively inner and outer, are separated by parting strips 16 attached to the proximate faces of guides 17, which are grooved to receive the sashes and form the inner walls of compartments 18 and 19 in which the sash counter balances 20 and 21 freely move, these elements being engaged with the sashes by cords 22 and 23 as usual.

In the preferred form of attachment each sash is provided with angle brackets 25-26, secured respectively to their lower and upper corners.

The bracket arms, parallel with the side edges of the sash, are provided with two spaced apart bearings to slidably receive pins 27-28 on which are fixed collars 29-30 abutting the ends of compression springs 31-32 encircling the rods and tending to retract or force them inwardly.

Hand grips 33-34 are fixed in the rods by which they may be projected or moved outwardly against the effect of the springs and also the grips may be engaged with catches 35-36, formed in the bracket, to retain the bars when extended.

The lower ends of the bars 27 are in register with sockets 37 set respectively in the cleat 13 and sill 12, and are adapted to bottom in the sockets, holding the sashes raised from the sill when so entered and forming one of the pivots for each sash.

The other, upper pivots, constituted by the pins 28, are adapted to engage in openings formed in a yoke 38 removably attached to the window frame.

5 The outer end of the yoke 38 has a slot 39 adapted to engage over the head of the turn bottom stud 40, set in a bracket 41 fixed on the window frame and locked thereto by turning the button head at a right angle.

10 The front end of the yoke is pivotally engaged to an arm 42, slotted at its free end to engage a similar turn bottom stud 43 set in the frame 10 in such location as to cause the yoke 38 to be substantially level when 15 operatively engaged.

15 Ordinarily the bars 27-28 are held in a retracted position by their encircling springs and the yoke 38 stored in any convenient place; when it is desired to cause the sashes to swing the yoke, is mounted in the frame 20 in the manner indicated and the pivot pins projected to engage the sockets and yoke cooperatively.

25 In Figs. 5, 6 and 7 brackets 50-51 are fixed on the sash and carry downwardly extending fixed pins 52-53, the lower being engageable in sockets 54-54' set in the cleat 13 and sill respectively, while the upper pins 53 engage in openings formed in brackets 33 30 hinged in recesses in the adjacent frame members.

35 These hinged eyes 55 are normally flush with the window frame but when it is desired to turn the sashes inwardly the sashes are raised till the pins 53 clear the eyes and the eyes may then be turned down for pivotal 40 reception of the pins, the eye brackets 55 serving as bearings and as limit stops to restrain the sashes from being lowered behind the sill stop bead.

45 The modification, shown in Figs. 8, 9 and 10, presents a combination of the previously described forms, the lower device being substantially the same as that indicated in Figs. 1 to 4 with the exception that the lower ends of the pins 27' are offset, as at 56, to facilitate swinging of the sash, while the upper pins 57-57'; set in bracket 58-58', are offset outwardly in alignment with the lower 50 pivot pins.

55 This is done for the purpose of clearing screw eyes 59-59', set in the sash frame to receive the pins, which in this case constitute hooks.

60 Obviously, the parting strip and stop bead on the opposite side of the window must be removed in order to permit the window sash to swing inwardly, and to facilitate its removal this element is provided with a plate catch, as at 60, cooperating with a turn button.

65 From the foregoing it will be seen that simple but effective means have been described by which an ordinary window furnished with slidable sash, may be inexpensive.

ly altered to permit the sash to swing at any time desired.

Having thus described the invention and set forth the manner of its construction and application what is claimed as new and sought to secure by Letters Patent, is:-

70 1. The combination with a window having a pair of sashes slidably mounted therein, of a bracket fixed on the inner face of said sashes at the corners adjacent one side edge, pivot pins 75 slidable in said brackets, resilient means for normally retaining said pins in a retracted position; means for moving said pins into projected operative position, sockets set in the window sill to receive the ends of the lowermost pins, thereby to retain the sash in a partially raised position, means for locking the pins when projected, a yoke having openings 80 to receive the uppermost pins, and means for detachably engaging said yoke to the window frame.

85 2. The combination with a window frame having one or more slidable sashes mounted therein, of spring impelled pivot pins carried by each sash at its upper and lower edges adjacent its side, means for normally retaining said pins when in an extended position, means set in the window sash to receive the ends of the lower of said pins when extended, a yoke having openings to receive the extended ends of the upper pins, means 90 for removably engaging said yoke to the window frame, and means for clamping said yoke when extended across the inner surface 95 of the frame adjacently above the window 100 sashes.

95 Signed at New York, in the county and State of New York, this 26th day of June, 1931.

105 FRED PICKEL.
